UNITED STATES PATENT OFFICE.

JOSEPH L. HECHT, OF DAVENPORT, IOWA, ASSIGNOR TO BETTENDORF METAL WHEEL COMPANY, A CORPORATION OF IOWA.

OIL-CUP.

No. 797,429.

Specification of Letters Patent.

Patented Aug. 15, 1905.

Application filed January 6, 1905. Serial No. 239,876.

To all whom it may concern:

Be it known that I, JOSEPH L. HECHT, of Davenport, county of Scott, and State of Iowa, have invented a new and useful Improvement in Oil-Cups, of which the following is a specification.

This invention has reference to lubricators in the form of an oil cup or reservoir adapted to communicate with the bearing to be lubricated and provided with a closure or cap arranged when open to permit the cup to be filled with oil and adapted when closed to effectually seal the cup against the escape of oil and the entrance of dust, sand, or other foreign substances.

The device is designed especially for application to wheel-hubs, pulleys, and analogous moving parts, but is applicable as well to other bearings, the improvement having especial reference to the form, construction, and arrangement of the closure or cap, as will be fully described and claimed.

In the accompanying drawings, Figure 1 is a longitudinal section through my improved device, showing the cap in closed position. Fig. 2 is a similar view showing the cap raised, so as to afford a communication between the outside and the oil-chamber for the introduction of the lubricant. Fig. 3 is a side elevation with the cap in closed position. Fig. 4 is a horizontal section on the line *a a* of Figs. 1 and 3.

1 represents an oil reservoir or cup, in the present instance of cylindrical form in cross-section and containing an oil-chamber 2, adapted to receive and contain a supply of oil and convey the same to the bearing to be lubricated, said oil-chamber extending longitudinally and entirely through the cup from end to end. The lower end of the cup is adapted for attachment to the bearing, and in the form shown it is provided with screw-threads arranged to be screwed into a wheel-hub, pulley, or like member. The upper end of the cup is closed by a cap 3, formed with a flat top 4 and an annular longitudinal band or rim 5, which fits closely but slidingly over the upper end of the cup 1, a packing-ring 6 being set in the upper end of the cup and a packing-disk 7 being seated in the cap so as to form a tight seal between the parts when the cap is in closed position, as shown in Fig. 1.

Formed in the annular surrounding ring or

band of the cap is a longitudinal slot 8, which I designate the "oil-feeding" opening, the function of which is to form a passage communicating with the interior of the oil-chamber when the cap is raised or in open position, the arrangement being such that when the cap is in this position the upper end of the slot will extend above the upper end of the cup, as shown in Fig. 2, in which position of the parts oil may be introduced through the opening to fill the chamber.

Projecting outwardly from the side of the cup is a stop-pin 9, the function of which is to limit the opening movement of the cap and to guide the same in its movements, this pin when the cap is elevated to its full extent being engaged by the lower end of the slot 8.

The cap is automatically closed after being raised and is held closed yieldingly by means of a spiral spring 10, extending centrally and longitudinally in the oil-chamber, with its upper end secured in any suitable manner to the flat top of the cap and its lower end secured to the cup, conveniently to a transverse pin 11 extending through and secured in the walls of the cup. The spring as thus applied will permit the cap to be raised, so as to bring the oil-feeding opening above the top of the cup, and when the cap is raised the spring will act to automatically draw it back and tightly close it against the upper end of the cup, the degree or stretch of expansion of the spring being limited and controlled by the stop-pin, with which the lower end of the slot will engage when the cap has been elevated to its full extent in order to bring the upper end of the feeding-opening above the cup.

I am aware that oil-cups have been provided with closing-caps acted on by a spring which serves to automatically close the cap and maintain the same yieldingly in closed position; but I believe myself to be the first to combine with these features a device adapted to limit the movement of the cap and the consequent stretch of expansion of the spring, with the result that the breakage of the spring or the separation of the parts is effectually prevented. While in the drawings I have shown this stop device in the form of a pin on the oil-cup adapted to be engaged by the end of the oil-feeding opening in the cap, it is manifest that other forms of stop devices may be employed without departing from the spirit of my invention, the essence of which resides

in a stop device so related and disposed that it will act to limit the degree of expansion or stretch of the spring and effectually prevent breakage of the same.

It is to be particularly observed that in my improved device the spring acts to hold the cap yieldingly in a closed position, it being necessary in order to open the cap to lift it against the restraining action of the spring. It will also be noted that the movement of the cap to open position is positively limited by the end of the feeding-slot encountering the stop 9. This is of peculiar advantage in connection with a cap which is held closed by the spring, for the reason that the stretch of the spring which takes place when the cap is opened cannot be such as to break it, and the cap is prevented from being lifted entirely off the cup. Further, by reason of the fact that the spring holds the cup closed there is no danger of the cup opening accidentally or from jarring, which would be the case if the spring tended to throw the cup to open position.

Having thus described my invention, what I claim is—

1. The combination with an oil-cup, of a cap therefor fitting the end of said cup and adapted to be moved outward to afford communica-

cation with the interior of the cup, a spring connected respectively with the cup and cap and acting to yieldingly restrain the cap against outward movement, said spring being adapted to be stretched when the cap is moved outwardly and means for limiting the outward movement of the cap and the consequent stretch of the spring.

2. In a lubricator the combination with a cylindrical oil-cup having its receiving end open, of a transverse pin extending through the oil-chamber thereof, and sustained by the walls of the cup, an outwardly-movable cap mounted slidably over the open end of the cup and formed in its side with an oil-feeding opening adapted, when the cap is moved outward, to extend beyond the upper end of the cup to permit of the introduction of oil, and a closing-spring fixed at one end to the cap and at its opposite end to the transverse pin, said spring being arranged to hold the cap yieldingly against outward movement.

In testimony whereof I hereunto set my hand, this 3d day of January, 1905, in the presence of two attesting witnesses.

JOSEPH L. HECHT.
